STOKER APPARATUS

William T. Hanna, Cincinnati, Ohio

Application August 19, 1942, Serial No. 455,327

9 Claims. (Cl. 110—105.5)

My invention relates to improvements in stoker apparatus and has to do, more particularly, with locomotive stokers for supplying a solid fuel, such as coal, to a locomotive firebox through a firing opening in the backwall thereof, and including fuel distributing apparatus associated with said opening and a conduit system for delivering fuel to said distributing apparatus.

In firing a locomotive the distribution of coal to the firebox should be balanced with respect to the vertical plane which includes the longitudinal center line of the firebox. Under usual conditions, a locomotive stoker should function to deliver equal volumes of coal, in equal units of time, to the firebox zones on opposite sides of said plane. When the coal is delivered to the distributing apparatus, through the firing opening, by a centrally-located conveyor screw working in the usual cylindrical conduit, it has been found that the fuel delivery is unbalanced with respect to said plane and more coal per unit of time is delivered to the zone on one side of said vertical plane, than to the other. This is probably due to the tendency of a conveyor screw working in a cylindrical conduit to deliver more coal through the portion of the conduit lying at one side of a vertical plane including the axis of the conveyor screw, than through the portion on the opposite side of said plane, and this tendency is thought to be due to the fact that the mass of coal, because of friction with the flight of the conveyor screw, tends to move circumferentially in a swirling movement.

The principal object of my invention is to provide a stoker apparatus which will, under all conditions, invariably deliver substantially equal volumes of fuel per unit of time to the distributing apparatus, on each side of the vertical plane including the longitudinal center line of the locomotive firebox, for distribution to the firebox zones on opposite sides of said plane.

A further object of my invention is to provide a locomotive stoker which will give this balanced delivery of fuel without any adjustment of any portion of the conduit system.

A further object of my invention is to provide a stoker apparatus of this character, giving balanced delivery of fuel, which is of simple design and sturdy construction, and can be manufactured at a relatively low cost.

Further objects, and objects relating to details of construction and economics of manufacture, will definitely appear from the detailed description to follow. In one instance, I have accomplished the objects of my invention by the

devices and means set forth in the following specification. My invention is clearly defined and pointed out in the appended claims. Structures constituting preferred embodiments of my invention are illustrated in the accompanying drawings, forming a part of this specification, in which:

Fig. 1 is a longitudinal, vertical, sectional view through one type of stoker apparatus embodying my invention, the conveyor screw section being shown in side elevation.

Fig. 2 is a sectional view, taken substantially on the line 2—2 of Fig. 1, the conveyor screw being shown in plan.

Fig. 3 is a view of the delivery end of the conduit system, substantially on the line 3—3 of Fig. 1.

Fig. 4 is a sectional view through the conduit section and the conveyor screw, taken substantially on the line 4—4 of Fig. 1.

Fig. 5 is a sectional view through the conduit section and the conveyor screw, taken substantially on the line 5—5 of Fig. 1.

Fig. 6 is a vertical, longitudinal, sectional view through another form of stoker apparatus embodying my invention, the conveyor screw being shown in side elevation.

Fig. 7 is a sectional view, taken substantially on the line 7—7 of Fig. 6, showing the conveyor screw in plan, and

Fig. 8 is a sectional view taken substantially on the line 8—8 of Fig. 6.

In the drawings, the same reference numerals refer to the same parts throughout the several views and the sectional views are taken looking in the direction of the arrows at the ends of the section lines.

I have shown my invention embodied in a locomotive stoker apparatus which includes fuel distributing apparatus, supported in or associated with the firing opening of the locomotive firebox, and a conveyor system which receives coal from the locomotive tender, and transfers and delivers it to the fuel distributing apparatus at the firing opening. This conveyor system is made up of a series of conduit sections within which conveyor screws turn. The delivery end of the foremost conduit section, from which the coal flows to the distributing apparatus, has a conveyor screw turning therein, the axis of which lies in the vertical plane including the longitudinal center line of the locomotive firebox. That is to say, the screw is located centrally with respect to the firing opening. My invention consists in the provision of a special formation for the interior of the

conduit section from which the fuel flows to the fuel distributing apparatus, such that the coaction of the conveyor screw therewith results in the balanced delivery of fuel to the distributing apparatus in the zones on opposite sides of said vertical plane. This special formation is such that a portion of the wall of the conduit section at one side of the vertical plane including the axis of the conveyor screw, is offset with relation to the portion of the wall on the opposite side of said plane. This offset formation should preferably be adjacent the delivery end of the conveyor screw and the conduit section. In the form illustrated, the offset formation is also below the axis of the conveyor screw. This offset formation of the wall serves to interrupt the swirling movement of the mass of fuel, which movement is induced within said conduit section by the rotation of the conveyor screw, and my invention contemplates any formation of the interior of said conduit section which serves to interrupt such swirling movement. I have obtained good results when the portion which interrupts the swirling movement of the mass of fuel lies substantially in the vertical plane including the axis of the conveyor screw and the longitudinal center line of the firebox and, as shown, below the axis. This formation results in the conduit section having a greater cross-sectional area on one side of said vertical plane than on the other and my invention contemplates any formation giving that result. It may be considered that this formation constitutes a baffle, which opposes the swirling movement of the fuel mass. More specifically, my invention contemplates the provision of a longitudinally extending shoulder on the wall of the conduit section, which resists the tendency of the mass of fuel to move circumferentially of the conduit section with the rotating screw. As stated above, good results were secured with this shoulder located substantially in the vertical plane including the axis of the conveyor screw and the longitudinal center line of the firebox and near the delivery end of the conduit section and the end of the conveyor screw.

My invention contemplates, further, the provision, with a conduit section formed as stated above and in which a conveyor screw rotates, of a pair of independently adjustable gates, pivoted near the vertical plane including the longitudinal center of the firebox, and one located on each side of said plane, for regulating the distribution of fuel to the firebox in the zones thereof on opposite sides of said plane. Each of these gates may be used to vary or regulate the distribution of the fuel within its zone and, also, to provide temporarily an unbalanced delivery of fuel under the unusual conditions where that may be desirable.

Referring to the numbered parts of the drawings, and more particularly to Figs. 1 to 5, inclusive, the backwall 16 of the locomotive firebox is provided with the usual firing opening 17. The deck of the locomotive is indicated at 28 and the deck of a coal bin on the locomotive tender is indicated at 13. Beneath the deck 13 is a hopper 11, having therein a coal-crushing or breaking device 12. The forward end of the hopper is connected by ball-and-socket joint to an intermediate or transfer conduit section 18. A sleeve 19 is slidably mounted on the forward end of the conduit section 18 and the forward end of said sleeve is formed into a ball, received within the socket of a conduit section 14a, thus forming a ball-and-socket connection between the two conduit sections 18 and 14a. The elevating conduit, indi-

cated generally at 14, is preferably formed in two conduit sections, a lower one, 14a, of usual construction, and an upper section, 14b, which has the special formation hereinafter described. Conduit sections 14a and 14b are supported from the backwall 16 of the locomotive firebox and fixed with respect thereto. A door housing 15 is secured to the backwall 16 surrounding the firing opening 17 therein. Conduit section 14a is supported by and secured to a portion of the housing 15 and is additionally supported by the bracket 31 secured to the boiler mudring 32, at the point where an expansion sheet 33 is also secured thereto. Housing 15 is provided with a rear wall 15b, the upper edge of which constitutes a delivery ledge 15a, over which fuel flows from the conduit system to the fuel distributing apparatus within the firing opening. Preferably, the upper portion of the door housing 15 is provided with a hand-firing opening 29, to the rear of and above the delivery ledge 15a, this opening being framed by a door plate 30 secured to the door housing and upon which may be mounted any one of the usual forms of automatic fire door (not shown).

25 A conveyor screw 21 is rotatable within the hopper 11, being driven by suitable means (not shown), and the forward end of said screw is connected by universal connection 22 to the rear end of a conveyor screw 23, which rotates within the conduit section 18. The forward end of said conveyor screw 23 is connected by universal connection 24 to the rear or lower end of conveyor screw 25, which turns within the conduit sections 14a and 14b. The upper end of conveyor screw 25 is tapered and it terminates slightly below the delivery ledge 15a.

30 Fuel distributing apparatus, indicated generally at 26, is supported within the firing opening 17 and immediately forward of and below the delivery ledge 15a. This apparatus comprises a vapor blast element 27, for instance, such as described in my U. S. patent, No. 2,090,-628, and a distributor plate 28, which may be of the construction shown in my U. S. patent, No. 2,128,940.

35 The conduit sections 18, 14a and 14b, together constitute a conduit system for transferring fuel from the hopper 11 to the firing opening, where it is delivered over the ledge 15a to the fuel distributing apparatus. Conduit section 18 is slightly inclined to the horizontal whereas the conduit sections 14a and 14b extend upwardly, at a considerably steeper angle, from a point below the deck of the locomotive to a point adjacent the lower portion of the firing opening.

40 Conduit section 14b is fixed to the upper end of conduit section 14a, as by means of bolts extending through mating flanges on said sections. The bottom wall 14d of said conduit section is spaced somewhat from the rear wall 15b of the door housing, to accommodate adjustable gates which will be described hereinafter. The internal cross-section of conduit section 14a is substantially circular, but the cross-sectional contour of the upper conduit section 14b is variable. At its junction with the lower conduit section 14a, it is substantially circular so as to match the passage in the lower conduit section. As shown in Fig. 2, the conduit section 14b expands laterally as it approaches the firing opening and, as shown in Figs. 3, 4 and 5, the bottom wall 14d flattens out until, at the firing opening, it is substantially flat as shown in Fig. 3. Part of the central portion of the top wall extends inwardly, as shown at 14c in Figs. 1 and 4, thus

forming a pair of channel portions which diverge toward the firing opening. The bottom wall 14d of conduit section 14b is provided with a longitudinally-extending internal shoulder 14e which, as shown in Fig. 1, extends from the lower end of conduit section 14b to a point opposite the end of conveyor screw 25 and, then, dies away. This shoulder lies substantially in the vertical plane including the axis of conveyor screw 25 and the longitudinal center line of the locomotive firebox. By reason of this shoulder, the portion of the inner wall of the conduit section, to one side of said vertical plane, is offset with respect to the portion of the inner wall on the opposite side of said plane, and the cross-sectional area of said conduit to one side of the plane is consequently greater than it is on the other. This shoulder is a formation which serves to interrupt the swirling movement of the coal in the conduit section, induced by the rotation of the conveyor screw 25, and it acts as a baffle opposing movement of the coal circumferentially of the conduit section. The direction of rotation of screw 25 is shown by the arrow in Fig. 5 and it will be noted that coal tending to move circumferentially with the rotating screw will move toward the shoulder 14e.

I believe that the unbalanced delivery of coal, from a cylindrical conduit in which a conveyor screw rotates, is due to the fact that the coal tends to move with the screw circumferentially of the conduit so that the fuel tends to concentrate on that side of the conduit toward which a point on the periphery of the screw, near the bottom wall of the conduit, moves as the screw rotates. By providing a conduit formation such that the cross-sectional area, on one side of the vertical plane including the axis of the screw, is greater than on the other, that portion of the conduit toward which a point on the periphery of the screw, near the bottom wall of the conduit, moves as the screw rotates, having the lesser cross-sectional area, I have introduced a resistance to this swirling movement of the coal and thus secured a balanced delivery. The shoulder 14e is an important factor in this action, as it offers resistance to this swirling movement and tends to interrupt it, but I have found by experience that the degree of resistance offered by the shoulder to interrupt the swirling movement may be varied as desired by varying the abruptness of the shoulder.

The upper edge of the bottom wall 14d forms a delivery ledge 14f, substantially in line with the delivery ledge 15a of the door housing 15. Coal forced upwardly in the conduit sections 14a and 14b flows over this delivery ledge to the fuel distributing apparatus. Interposed between the bottom wall 14d of conduit section 14b, and the rear wall 15b, there is a pair of independently adjustable gates 34 and 35. These gates are pivoted near the vertical plane including the axis of the conveyor screw as indicated at 36 and 37 (Fig. 2) and move in a plane parallel to the wall 15b. These gates may be adjusted so that their upper edges are substantially parallel with the delivery ledges 15a and 14f or to other positions, as indicated in Fig. 2, in which case the upper edges of said gates form portions of the delivery ledge over which the fuel flows to the distributing apparatus. To facilitate manipulation of these gates, they are provided with handle extensions 34b and 35b and they may be retained in adjusted positions by the dog screws 38, threaded into the side walls of the door housing 15, and engaging

notches 34a and 35a in the respective gates. These independently adjustable gates provide means for regulating the distribution of fuel to the respective firebox zones lying on opposite sides of the vertical plane including the longitudinal center line of the firebox, and also make it possible to modify temporarily the balanced delivery to said zones provided by the conveyor screw working in the conduit section of special formation, to meet unusual conditions as hereinbefore described. The main function of these gates is to control the volume of fuel delivered to the sides of the firebox relative to the volume delivered near the center.

15 To close the gap between the upper side surfaces of conduit section 14b and the side walls of the door housing 15 closure sealing members 39 and 40, respectively, are provided which are secured, in any suitable manner, to the door housing, preferably by bolting to the side walls thereof.

20 In Figs. 6 to 8, inclusive, I have shown my invention embodied in another type of stoker apparatus. This includes a transfer conduit 118 upon which a sleeve extension 119 is slidably mounted, the forward end of this sleeve extension being connected by a ball-and-socket joint with a riser conduit 140. The upper end of the latter is provided with a headpiece 141, which serves as a continuation thereof and is secured to the outer face of the backwall 16 of the locomotive firebox, having a firing opening 17. A conveyor screw 123, driven in any suitable manner, is rotatable within the conduit 118 and the forward end thereof is connected, by universal connection 124, to a conveyor screw 125 which rotates within the conduit section 140 and headpiece 141. The direction of rotation is indicated by the arrow in Fig. 8. The upper end of this conveyor screw is tapered and terminates substantially at the firing opening. Fuel distributing apparatus comprising the distributor plate 128 and the blast member 127 is supported within the firing opening, at the upper end of the conduit section 140 and, in this instance, the coal delivered flows over the end portion 141a of the lower forward wall 141b of headpiece 141, and over the upper surface 121a of the blast member 127 to the distributing apparatus. The riser conduit 140 is supported by its attachment to headpiece 141 and by a bracket 131 mounted upon the mudring 32, at the point where expansion sheet 33 is secured thereto.

25 In this form of apparatus, also, the axis of conveyor screw 125 lies in the vertical plane which also includes the longitudinal center line of the firebox, so that the conduit 140 and conveyor screw 125 are centrally located with respect to the firing opening. In order to provide a balanced delivery of fuel through the firing opening, that is to say, the delivery of equal volumes of fuel on opposite sides of said vertical plane, I have provided the inner wall of conduit section 140, and the conduit portion of headpiece 141, with a special formation. As shown, a shoulder 140c is provided in the bottom wall 140b of conduit 140, which shoulder is continued as 141c in the lower forward wall 141b of the headpiece 141, and said shoulder extends from the lower end of conduit 140 to a point adjacent the lower edge of the firing opening, where it dies away. As shown in Fig. 8, this shoulder results in offsetting a portion of the bottom wall of the conduit section, on one side of said vertical plane, with respect to the portion on the other side thereof and forms a baffle interrupting or resisting the swirl-

ing movement of the coal induced in the conduit section by the rotation of the conveyor screw.

Any form of suitable closure may be provided for the upper portion of firing opening 17, such as a door ring 150 and a door 151. The headpiece 141 is provided with trunnions upon which the deflectors or wings 134 and 135 are pivotally mounted. These deflectors are adjustable into various angular positions by means of adjusting screws 134a and 135a, threaded into the walls of the headpiece 141 and engaging lugs projecting from the wings 134 and 135, respectively. These wings or deflectors may be adjusted to control the lateral extent of the coal stream flowing over the blast member, so as to provide a more or less restricted delivery pathway.

Operation of my improved stoker apparatus should be very clear from the foregoing description. Coal from the locomotive tender 13 is fed into the hopper 11 and the rotation of the conveyor screw system transports the fuel past the breaker 12, which crushes the larger lumps into proper size, and then through the transfer conduit 18 into the elevating conduit 14, comprising the lower section, 14a, and the upper section, 14b. The fuel carried upwardly in these conduit sections by the rotating screw 25 is delivered over the delivery ledges 14f and 15a to the fuel distributing apparatus in the firing opening 17, which functions to distribute the coal to the various portions of the fire bed. The tendency of the coal to move circumferentially of conduit section 14b, or to acquire a swirling movement therein, because of the rotation of conveyor screw 25, is interrupted or resisted by the constriction formed by the shiulder 14e, with the result that the coal flows from the delivery end of said conduit section in a balanced manner, approximately equal volumes, in equal units of time, being delivered on opposite sides of the vertical plane including the longitudinal center of the locomotive firebox. It should be understood that, although it is desirable to equalize the volumes of coal delivered on opposite sides of said vertical plane, it is not necessary or desirable to distribute the coal uniformly over all portions of the fire bed. This distribution, in each of the to zones on opposite sides of said vertical plane, is regulated by the adjustable gates 34 and 35, one for each of said zones, respectively. The operation of the embodiment shown in Figs. 6 to 8, inclusive is substantially the same as that already described, but, in this case, instead of the adjustable gates 34 and 35, the deflector wings 134 and 135 are employed.

I am aware that the apparatus here shown is susceptible of considerable variation without departing from the spirit of my invention and, therefore, I claim it broadly as indicated by the appended claims.

What I claim is:

1. In a locomotive stoker for supplying solid fuel to a fire box through a firing opening in the back wall thereof, including fuel distributing apparatus associated with said opening, a conduit system for delivering fuel to said distributing apparatus comprising the combination of a conduit section from which fuel flows lengthwise of the section to said distributing apparatus, a conveyor screw rotatable within said conduit section and terminating therein, a portion of the wall of said conduit section, adjacent the delivery end of said screw and at one side of the vertical plane including the axis of said screw, being offset inwardly with relation to the ad-

jacent portion of the wall on the opposite side of said plane, and means for driving said screw in a direction to cause a point on the periphery thereof next to said adjacent portion to move toward said inwardly offset portion, whereby said conduit system delivers substantially equal volumes of fuel on both sides of said plane.

2. In a locomotive stoker for supplying solid fuel to a firebox through a firing opening in the back wall thereof, including fuel distributing apparatus associated with said opening, a conduit system for delivering fuel to said distributing apparatus comprising the combination of a conduit section from which fuel flows to said distributing apparatus, a conveyor screw rotatable within said conduit section and with its axis lying substantially in a vertical plane including the longitudinal centerline of said firebox, a portion of the wall of said conduit section, adjacent the delivery end thereof, and below said axis and at one side of said plane, being inwardly offset with relation to the adjacent portion of the wall below said axis and on the opposite side of said plane, and means for driving said screw in a direction to cause a point on the periphery thereof next to said adjacent portion to move toward said inwardly offset portion, whereby said conduit system delivers substantially equal volumes of fuel on both sides of said plane.

3. In a locomotive stoker for supplying solid fuel to a firebox through a firing opening in the back wall thereof, including fuel distributing apparatus associated with said opening, a conduit system for delivering fuel to said distributing apparatus comprising the combination of a conduit section from which fuel flows to said distributing apparatus and a conveyor screw rotatable within said conduit section and having its axis lying substantially in the vertical plane including the longitudinal centerline of said firebox, a portion of the inner wall of said conduit section in said plane and adjacent the delivery end of said conduit section being so formed as to interrupt the swirling movement of the mass of fuel induced within said conduit section by rotation of said screw and thereby equalize the delivery of fuel on opposite sides of said plane.

4. In a locomotive stoker for supplying solid fuel to a firebox through a firing opening in the back wall thereof, including fuel distributing apparatus associated with said opening, a conduit system for delivering fuel to said distributing apparatus comprising the combination of a conduit section, fixed with respect to said opening, from which fuel flows to said distributing apparatus and a conveyor screw, rotatable within said conduit section and having its axis lying substantially in the vertical plane including the longitudinal centerline of the firebox, a portion of said conduit section, adjacent the delivery end thereof and surrounding said screw, being so formed as to have a lesser cross-sectional area on that side of said plane toward which a point on the periphery of the screw adjacent the bottom wall of the conduit section moves as the screw turns, than on the opposite side of said plane, whereby the delivery of fuel on opposite sides of said plane is equalized.

5. In a locomotive stoker for supplying solid fuel to a firebox through a firing opening in the back wall thereof, including fuel distributing apparatus associated with said opening, a conduit system for delivering fuel to said distributing apparatus comprising the combination of a conduit section from which fuel flows to said

distributing apparatus, and a conveyor screw, rotatable within said conduit section and having its axis lying substantially in the vertical plane including the longitudinal centerline of the firebox, a portion of the wall of said conduit section adjacent the delivery end thereof and lying substantially in said plane being so formed as to constitute a baffle opposing the swirling movement of the fuel mass induced within the conduit section by rotation of said screw, whereby delivery of fuel on opposite sides of said plane is equalized.

6. In a locomotive stoker for supplying solid fuel to a firebox through a firing opening in the back wall thereof, including fuel distributing apparatus associated with said opening, a conduit system for delivering fuel to said distributing apparatus comprising the combination of a conduit section from which fuel flows to said distributing apparatus, a conveyor screw, rotatable within said conduit section and having its axis lying substantially in the vertical plane including the longitudinal centerline of the firebox, a portion of the wall of said conduit section near the delivery end thereof having a longitudinally extending shoulder substantially in said plane, and means for driving said screw in a direction such that it tends to move fuel circumferentially of the conduit section against said shoulder, whereby delivery of fuel on opposite sides of said plane is equalized.

7. A conduit section for use as a part of the fuel-delivery system of a locomotive stoker having into a bottom wall, curved near the intake end and substantially flat at the delivery end of said section, said bottom wall terminating at the de-

livery end in a delivery ledge, side walls diverging from the intake to the delivery end, a top wall sloping toward the bottom wall from the intake to the delivery end, an intermediate portion of said top wall extending inwardly of the conduit section forming in conjunction with the side walls a pair of channels in the top wall diverging toward the delivery end, and an internal shoulder extending longitudinally of the bottom wall, approximately midway between the side walls, perpendicular to said delivery ledge, from the intake end to a point near the delivery end of said section.

8. A conduit section for use as a part of the fuel-delivery system of a locomotive stoker having a bottom wall terminating in a delivery ledge at the delivery end of said section, side walls diverging from the intake to the delivery end, a top wall formed so as, in conjunction with the side walls, to give in effect a pair of channels diverging toward the delivery end, and an internal shoulder extending longitudinally of the bottom wall, approximately midway between the side walls, perpendicular to said delivery ledge, from the intake end to a point near the delivery end of said section.

9. A conduit section for use as a part of the fuel-delivery system of a locomotive stoker having a bottom wall terminating in a delivery ledge at the delivery end of said section, side walls, a top wall and an internal shoulder extending longitudinally of the bottom wall and lying substantially in a vertical plane perpendicular to said delivery ledge.

WILLIAM T. HANNA.
